UNITED STATES PATENT OFFICE.

WILLIAM M. ZIEGLER AND ALFRED G. SUDHOFF, OF RICHMOND, INDIANA, ASSIGNEES
TO THE NATIONAL AUTOMATIC TOOL CO., OF RICHMOND, INDIANA, A CORPOR-
ATION OF INDIANA.

ROTATING TABLE FOR DRILLING-MACHINES AND THE LIKE.

1,367,579.

Specification of Letters Patent.

Patented Feb. 8, 1921.

Application filed March 10, 1920. Serial No. 364,810.

To all whom it may concern:

Be it known that we, WILLIAM M. ZIEGLER and ALFRED G. SUDHOFF, citizens of the United States, residing in Richmond, in the county of Wayne and State of Indiana, have invented certain new and useful Improvements in Rotating Tables for Drilling-Machines and the like, of which the following is a specification.

10 The object of the present invention is to more adequately provide for disposal of lubricant and chips than has heretofore been done, in machines employing rotary work-tables, such for example as a multiple 15 drill. An example of a machine of the general character of that in connection with which this present invention has been developed may be seen in the Stephenson Patent No. 1,012,024 issued December 19, 20 1911, though that patent does not exhibit a rotary work-table. Machines containing the Stephenson invention have been quite extensively used which do have a rotary work-table, and in many uses of such a machine, and particularly in drill practice as carried on in some manufacturing establishments, lubricant is used very copiously with the result that in rotation of the work-table it is apt to be thrown off to the 25 comfort of the workman and to the detriment of his operations and also resulting in material loss as to recovery of lubricant. In some instances drain-holes have been provided screened to catch the chips but 30 this custom has been attended with more or less inconvenience and difficulty in the matter of removal of the chips, besides which their accumulation interferes with the ready-flowing off of the lubricant.

40 By the present invention provision is made for free and continuous flow of both lubricant and chips and their ready disposal without any chance of lubricant being thrown off the table. In carrying out 45 the present invention in the form here shown large openings are formed in the inner wall of the usual encircling oil gutter and passages lead from these openings inwardly and discharge into other passages 50 in the base upon which the table is mounted, whence the lubricant, carrying the chips along with it, flows to the sub-base where it

can collect in a suitable space provided for the purpose and from which it can be removed, the chips being scooped out as occasion may arise. 55

In the drawings which accompany and form part of this specification, Figure 1 represents in perspective a table, base and sub-base; Fig. 2 is a vertical cross-section 60 taken substantially on the line 2—2 of Fig. 1; Fig. 3 is a bottom plan view of the table; Fig. 4 is a fragmentary section taken substantially on the line 4—4 of Fig. 3; Fig. 5 is a top plan view of the base; Fig. 6 is 65 a vertical section taken substantially on the line 6—6 of Fig. 5, and Fig. 7 is a vertical section taken substantially on the line 7—7 of Fig. 5.

The numeral 2 designates in general the 70 sub-base which rests upon the floor, 3 the base proper which is mounted upon said sub-base, and 4 the rotating table. The latter is of circular form and has the usual encircling oil gutter 5. Large openings 6 75 are made in the inner wall of this gutter at frequent intervals and radial passageways 7 extend inwardly from these openings. One of these passageways appears clearly in Figs. 2 and 4 and will be seen 80 to be closed all around for some distance toward the center of the table. It leads to a fairly wide space between webs 8 of the table casting, which space is fully open at the bottom providing a spacious outlet 7^a 85 for oil and chips flowing down the passageway 7, the bottom of the latter being inclined downwardly toward the center of the table as clearly shown in Fig. 2. By reference to Fig. 3 it will be seen that an 90 ample number of these oil passageways and discharge openings is provided, six being there shown as alternating between webbed sections of the table casting.

The table is mounted to turn upon the 95 base 3 which at its upper part is of circular form, the lower part being of rectangular form. This base is cast with a number of radiating webs 9 and it is fully open at the top between these webs in such manner as 100 to register with the large discharge openings 7^a of the table, as clearly shown in Fig. 2. The spaces 10 in the base casting between the webs provide large passageways

for the oil and chips discharged through said table openings, the bottoms of these large passageways are inclined so as to carry the oil and chips outwardly for their discharge upon the sub-base 2 which is hollow and thus serves as a reservoir for the oil and chips. It may be rendered sufficiently open above in any suitable manner to give access for recovery of the oil and removal of the chips. At one side of the base 3 certain table controlling mechanism is mounted comprising a treadle 11 and operating connections for elevating the table, and a lever 12 and suitable connections for coöperating table indexing means to fix the position of the table. This mechanism forms no part of the present invention, and is shown and here mentioned merely because its presence occasions a somewhat different formation of the base at this side thereof from its formation elsewhere for the disposal of the oil and chips flowing down from the table passageways. At the other three sides of the base the passageways simply extend down and outwardly between the webs 9 as shown in Figs. 5 and 6; 13 designating their sharply sloping bottoms. At the side where the table-controlling mechanism is located the space required to accommodate that mechanism eliminates one web. Here the oil receiving opening is double the width of other such openings and the passageway, instead of having a flat outward-sloping bottom like the other passageways, has a divided character, the bottom surface sloping in opposite direction and at right angles to what the slope would be if this passageway was just like the others. This is best illustrated in Fig. 7 where the numeral 14 designates the oppositely sloping surfaces. There is a somewhat different conformation in cross-section at right angles to this figure of the drawings, as compared with other parts of the base, which difference in conformation is also occasioned by the necessity for accommodating the table controlling mechanism before mentioned. This appears quite clearly in Fig. 2 at 15, as a bowl-like formation with end walls formed by webs 9. See also Fig. 5. Outlet openings 16 are made in these webs for the escape of oil flowing down the oppositely sloping surfaces 14, which discharges upon the subjacent surfaces 13.

It will be noted that the openings in the inner wall of the oil gutter encircling the table are of ample proportions, so much so as to provide for ready flow of oil and chips through them. No screens are used over them and there is no opportunity for oil and chips to accumulate in the gutter and so far fill the same as to result in overflow, and there is no opportunity for oil to be thrown off the table as the latter is rotated.

It has already been mentioned that these large openings occur at frequent intervals, and it will be obvious that the character of the passageways 7 is such as to provide for a ready flow of oil and chips from the openings 6 inwardly toward the center of the table, and likewise that the discharge openings are of ample proportions, as are also the receiving openings at the top of the passageways in the base, so that oil and chips flowing inwardly down the passageways 7 will freely discharge into the passageways of the base, and the latter are of such character as to provide for immediate discharge of the oil and chips unto the sub-base. It will be obvious therefore that the rotating table and the base are kept free at all times from accumulation of chips and that there can be no choking of oil flow or any escape of oil except by way of the passageways which lead it to the reservoir in the sub-base, so that complete recovery of lubricant is made possible.

It will now be apparent that the structure shown and described is well adapted to thoroughly fulfil the object primarily stated, but at the same time it is of course to be understood that the form of embodiment of the invention here detailed has been worked out in connection with one particular use and there may be various more or less differing adaptations of the invention to other situations.

We claim:

1. The combination of a rotary work table having an encircling channel and subjacent inwardly extending drain passages, and a stationary base having passageways registering with outlets of the said drain passages at the inner ends thereof.

2. The combination of a rotary work table having an encircling channel and subjacent inwardly extending radiating drain passages communicating at their outer ends with said channel and having discharge openings in their under sides at their inner ends; and a stationary base having downwardly and outwardly directed passageways registering with the said discharge openings of the drain passages.

3. The combination of a rotary work table having an encircling channel and radiating webs on its under side with oil passageways between webs and closed around for a distance inward, the space beyond between the webs being open; and a stationary base on which the table turns, said base having radiating webs and open spaces between them to register with those between webs of the table, and discharge passageways leading from open spaces downwardly and outwardly.

4. The combination of a rotary work table having an encircling channel and radiating webs on its underside with oil passageways

between webs and closed around for a distance inward, the space beyond between the webs being open; and a stationary base on which the table turns, said base having 5 radiating webs and open spaces between them to register with those between webs of the table, and discharge passageways leading from open spaces downwardly and outwardly, one such passageway dividing and extending in opposite direction to openings in opposite sides of the base.

WILLIAM M. ZIEGLER,
ALFRED G. SUDHOFF
